UNITED STATES PATENT OFFICE

2,542,509

TOY WASHING MACHINE OF THE
OSCILLATING DRUM TYPE

Frank J. Goriup, Pittsburgh, Pa., assignor to
Wolverine Supply and Manufacturing Company,
Pittsburgh, Pa., a corporation of Pennsylvania

Application July 8, 1948, Serial No. 37,597

1 Claim. (Cl. 68—153)

1

The principal object which I have in view is the provision of a toy of such character which will operate on the principle of a tumbling drum type of domestic washing machine.

In the present toy machine, I provide a tub in which a drum is mounted on a horizontal axis, the clothes to be washed being loaded into the drum, and novel means are provided for imparting to the drum rotary movement in alternate directions.

Improved means are provided for mounting the drum in the tub and also for imparting the alternate rotary movements to the drum.

Other novel features of construction and arrangement of parts will appear from the following description.

In the drawings:

Fig. 1 is a front elevation of the washing machine;

Fig. 2 is a vertical section taken along the line 2—2 in Fig. 1;

Fig. 3 is a section on enlarged scale taken along the line 3—3 in Fig. 2;

Fig. 4 is a partial sectional view taken along the line 4—4 in Fig. 2, and

Fig. 5 is an elevation of the operating crank dismounted.

Referring to the drawings, 10 indicates the tub which is formed of sheet material and is shown as of rectangular shape comprising the front wall 11, the side walls 12 and 13, which latter are duplicates in form, and the rear wall 14.

The front and side walls may be integrally formed by bending a sheet metal blank along the vertical lines, while the rear wall 14 may be a separate blank fastened to the side walls by the tongues 15 integral with the side walls and extending through slots in the rear wall and bent down against the outer surface of said side wall.

The tub is provided with a horizontal lower perimetral edge so that it may stand steady on the floor or table.

Thus the tub may be formed of stamped metal sheet material and may be quickly assembled to complete the tub.

The tub is provided with a floor 16 which fits between the walls and is held in place in a similar manner by means of the tongues 15 integral with the floor and extending through slots in the walls and then bent down. The floor is preferably elevated above the lower end of the tub as illustrated in the drawings.

17 indicates the removable cover for the tub, being provided with a depending perimetral flange which fits down over an upwardly extend-

ing top flange of the tub. These flanges are tubular and thus resiliently engage each other to prevent accidental loosening of the cover.

The front wall 11 of the tub 10 is provided with a relatively large circular opening 18 and the perimetral edge of said opening is bent inwardly to form a cylindrical bearing 19. The rear wall 14 of the tub is provided with a small bearing hole 20 axially aligned with the opening 18 in the front wall.

The drum 21 is formed of sheet metal bent up into cylindrical shape with the ends of the sheet secured together as by soldering.

The front end of the drum is formed by the annular wall 22 secured as by soldering to the cylindrical body of the drum 21 and being provided at its free edge with an outwardly extending annular portion 23 which is journaled in the bearing 19. The free extremity of the portion 23 is bent at right angles to the journal portion 23 to form a lip 24 against which outwardly bears the circular glass plate 25 of proper diameter to fit in the portion 23. The glass plate 25 is held in place by an annular keeper plate 26 of proper diameter to fit in the interior of the circular drum. The plate 26 is provided with an annular flange 27 which fits into the cylindrical portion 23 of the wall 22 and is provided with an annular terminal lip 27a which extends inwardly in a plane parallel with the glass plate 25 and bears against the inner surface of the glass plate 25 to hold it firmly in position.

28 indicates a rubber gasket ring which is compressed between the glass plate and the lip 24 to prevent the escape of water or moisture from the end of the drum.

The opposite end of the drum is closed by the circular wall 29 which is provided at its center with a circular inwardly pressed portion 30. 31 indicates a circular plate which is riveted or otherwise secured to the outer face of the wall 29, and 32 indicates a gudgeon having its enlarged circular base rigidly secured to the plate 31, the gudgeon extending outwardly therefrom in axial alignment with the annular portion 23 of the other end wall of the drum. The gudgeon 32 for the greater part of its length is of rectangular cross-sectional shape but at the inner and outer extremities of the gudgeon, the latter is preferably cylindrical. The outer end of the gudgeon is journaled in the bearing hole 20 in the rear wall 14.

The drum is of less length than the horizontal depth of the tub and within this space a boxing 33 is fixed on the gudgeon. This boxing con-

sists of two spaced parallel wings 34 connected at one end by a web 35 and adjacent said web the wings are rigidly connected along their longitudinal edges by the rectangular plates 36 provided with registering rectangular holes 37 through which the gudgeon extends, thus assembling the boxing and the gudgeon to rotate in unison.

38 indicates the operating handle formed of a steel rod and provided at its outer end with a hand grip 40. The reference number 39 indicates a portion of the steel rod connected to the handle 40 and extending at a right angle to the latter. Merging with the portion 39 is a straight portion 41 which extends through a bearing hole in the side wall 13. The inner extremity of the operating handle is provided with an inclined portion 42 ending with a straight portion 43 parallel with the hand grip 40 but misaligned in respect thereto. The portion 43 projects inwardly between the wings 34 of the boxing 33 with sufficient clearance provided by the spacing of the wings, so that as the crank handle is turned the boxing 33 is swung first in one direction and then in the other, causing the drum to oscillate on its axis and thus wash the clothes which have been introduced into the drum with the washing water and soap.

44 indicates a circular sheet metal cage having a perimetral wall which is provided with spaced tongues 45 which are inserted through slots in the rear wall 14 of the tub and bent over to attach the cage to the inner surface of the wall and concentric with the bearing hole 20 in which the outer extremity of the gudgeon is journaled. The cage is closed at its inner end by its rear wall 46 which is provided with an axial opening 47 through which the gudgeon is journaled. The perimetral wall of the cage is provided with a properly located bearing hole 48 through which the portion 41 of the operating handle extends, the handle being thus journaled in the side wall of the tub and in the perimetral wall of the cage.

The upper portion of the cylindrical wall of the drum is provided with an oval access opening 49 which is closed by the lid 49 hinged at 50. 51 indicates a catch to hold the lid open.

The interior of the drum is provided with the longitudinally extending ribs or baffles 52 which agitate the clothes as the drum is oscillated.

53 indicates rollers which are mounted in stands 54 on the floor 46 of the lid and support the drum from beneath.

The perimetral wall of the cage 44 is provided with spaced ports 55 which prevent the accumulation of water or moisture in the cage.

When the toy washing machine is to be used, the cover is removed and the lid of the drum

swung aside to expose the access opening, the water and soap are introduced into the interior of the drum together with the clothes to be washed. The lid is then swung into its closed position and latched, and the operator seizes the operating handle and rotates the same, thus oscillating the drum and accomplishing the washing operation. When the clothes are properly cleansed the cover is lifted off and the lid swung open to permit the removal of the clothes, and the toy is inverted to drain off the washing solution.

The toy washing machine is inexpensive to manufacture and is sufficiently rigid to prevent its easy impairment or destruction.

I claim:

In means for supporting a rotary drum on a horizontal axis in the tub of a toy washing machine, the combination of an inwardly extending annular flange defining a circular opening in the wall of the tub, an outwardly extending annular flange defining an opening in the adjacent end wall of the drum, said outwardly extending annular flange being journaled in said inwardly extending annular flange, said outwardly extending annular flange being provided with an annular terminal lip extending radially into said opening in the wall of the drum, a circular plate of glass inserted into said outwardly extending annular flange, a gasket interposed between the glass plate and the lip, a keeper ring pressed into said outwardly extending annular flange to hold the glass plate in position, a gudgeon fixed to the opposite end wall of the drum and disposed axially thereof, means defining a bearing in the adjacent wall of the tub in which the gudgeon is journaled, and means engaging said gudgeon for imparting an oscillatory movement to the gudgeon.

FRANK J. GORIUP.
